UNITED STATES PATENT OFFICE.

FRANK S. BALATTA, OF ST. PAUL, MINNESOTA.

APPARATUS FOR CONVEYING THE EXHAUST GASES OF AN INTERNAL-COMBUSTION ENGINE FROM A GARAGE.

Application filed April 16, 1925. Serial No. 23,549.

To all whom it may concern:

Be it known that I, FRANK S. BALATTA, a citizen of United States, residing at St. Paul, in the county of Ramsey and State of Minnesota, have invented certain new and useful Improvements in Apparatus for Conveying the Exhaust Gases of an Internal-Combustion Engine from a Garage; and I do hereby declare the following to be a full, clear, and exact description of the invention, such as will enable others skilled in the art to which it appertains to make and use the same.

My present invention has for its object to provide a safe and highly efficient apparatus for conveying the deadly exhaust gas of an internal combustion engine, when stationed in a garage or other building, to the outside thereof.

To the above end, the invention consists of the novel devices and combinations of devices hereinafter described and defined in the claims.

In the accompanying drawings, which illustrate the invention, like characters indicate like parts throughout the several views.

Referring to the drawings:

Fig. 1 is a view partly in central vertical section and partly in diagram showing a garage and a motor-propelled truck having the invention embodied therein;

Fig. 2 is a plan view of the apparatus with some parts broken away and other parts sectioned on the line 2—2 of Fig. 1, on an enlarged scale;

Fig. 3 is a view partly in left side elevation and partly in vertical section taken on the line 3—3 of Fig. 2; and

Fig. 4 is a view corresponding to Fig. 3 but showing the frame of the apparatus collapsed.

The numeral 5 indicates a garage having at one end a door 6 and at its other end a stop block 7. Within the garage 5 is an internal combustion-engine-propelled truck 8, the driving shaft case and exhaust pipe of which are indicated by the numerals 9 and 10, respectively. A muffler 11 is interposed in the exhaust pipe 10. The parts thus far described have been illustrated simply for the purpose of showing the invention applied in working position.

Interposed in the exhaust pipe 10 forward

of the muffler 11 is a cut-out including a T-shaped casing 12 having an exhaust port 13 connected by a short hose section 14 to an underlying forwardly projecting exhaust nozzle 15. This exhaust nozzle 15 is held suspended from the driving shaft casing 9 by a pair of hanger brackets 16. In the discharge end of the exhaust nozzle 15 is a conical spider 17. Mounted in the cut-out casing 12 is a hinged valve-acting blade 18 having on its hinge pin a crank arm 19. The valve-acting blade 18 is actuated by a spring 19' to close the exhaust port 13 to the nozzle 15 so that normally the exhaust gases pass through the cut-out casing 12 to the muffler 11. For operating the valve-acting blade 18, to close the exhaust pipe 10 to the muffler 11 and thereby cause the exhaust gases to pass through the port 13, hose 14 and nozzle 15, I provide a vertically disposed tripping lever 20 intermediately pivoted to the forward hanger bracket 16 and having its short or upper end connected by a cable 20' to the crank arm 19. This tripping lever 20 is gravity-held and automatically operated in a manner that will hereinafter appear.

Supported on the floor of the garage 5 is a collapsible frame comprising a skeleton rectangular base 21 to the corners of which are pivoted four upright posts 22, opposite pairs of which are connected by front and rear tie rods 23. These two tie rods 23 are connected at their ends by a pair of end tie bars 24 and which in turn are connected by an intermediate angle bar 25.

The collapsible frame is rigidly secured to the floor of the garage 5 by lag screws 26 and is arranged to be collapsed by a swinging movement toward the front of said garage. Stop fingers 27 on the rear pair of posts 22 are arranged to engage the floor of the garage 5 and limit the collapsing movement of the frame. The collapsible frame is provided with a pair of counterbalancing springs 28 anchored to the rear posts 22 and the upturned rearwardly extended end portions of the end members of the frame 100 base 21.

Overlying the tie rods 23 is a carriage 29 which, as shown, is in the form of a flat plate having depending apertured ears 30 through which said rods project to afford track rails on which said carriage is free

to slide. Secured to the top of the carriage 29 and suitably braced is a pair of converging abutment plates 31. Located at the rear of the carriage 29, between the converging abutment plates 31, is an exhaust head 32 having a flaring mouth 33 adapted to receive the exhaust nozzle 15, as best shown in Fig. 3. This exhaust head 32 is provided with a downwardly and forwardly (in respect to the garage 5) extended neck 34 to which is attached a hose 35 which lies in an open trough 36 in the floor of the garage 5 and extends outside of said garage through one side thereof. The exhaust head 32 is pivotally attached to the carriage 29 by a bail-like member 37 pivoted to depending ears 38 on the bottom of the carriage 29 for vertical swinging movement. The intermediate portion of the bail 37 is contracted onto the sides of the neck 34 and which neck is pivoted thereto at 39. The bail 37 holds the exhaust head 32 for movement transversely of the travelling movement of the carriage 29. A pair of coiled springs 40 anchored to the abutment plates 31 and attached to the exhaust mouth 33, yieldingly hold the exhaust head 32 drawn forward with the mouth 33 resting on the carriage 29 as a stop. A fork-like plate 41 secured to the carriage 29 holds the exhaust head 32 against lateral movement but with freedom for the pivotal and lifting movements, as permitted by the bail-like member 37. The carriage 29 is yieldingly held in a central position and returns to the position by a coiled spring 42 and a cable 43 having their adjacent ends connected. The other end of the spring 42 is anchored to the frame angle bar 25 and the other end of the cable 43 is attached at 44 to the carriage 29. Said cable 43 is arranged to run over a pair of guide sheaves 45 journaled on the frame angle bar 25. These guide sheaves 45 are so arranged as to cause the spring 42 to return the carriage 29 to a central or normal position when said carriage is moved either to the left or right. Normally the frame is collapsed, as shown in Fig. 3, and to automatically set the same up, under a movement of the truck 8, there is provided a depending swinging arm 46 pivoted to a clamp 47 applied to the propeller shaft casing 9. A T-shaped hook 48 is pivoted to the free or lower end of the arm 46 and is yieldingly held in an intermediate position by a coiled spring 49 anchored to said arm. This hook 48 is arranged to engage an upstanding bail 50 which spans the abutment plates 31 and is rigidly secured to the carriage 29, and set up the collapsed frame during the movement of the truck 8 into the garage 5. The bail 50 is further held by brace bars 51 anchored to the carriage 29. Chains 52 at-

tached to the rear posts 22 and anchored to the frame base 21 act as stops for the frame during its setting-up movement.

Operation.

As previously stated, the frame is normally collapsed, as shown in Fig. 3. During the forward movement of the truck 8 into the garage, the hook 48 engages the bail 50 and lifts the frame until stopped by the chains 52. At the time the upsetting movement of the frame is stopped by the chains 52, the hook 48 is tripped out of engagement with the bail 50 and the released arm 46 swings into a vertical position. At the completion of the setting up of the frame, the exhaust nozzle 15, under the continued forward movement of the truck 8, enters between the abutment plates 31; and if said nozzle is not aligned with the flaring mouth 33 of the exhaust head 32, it engages either one of said abutment plates and thereby shifts the carriage 29, against the tension of the spring 42, to align said mouth so that the exhaust nozzle 15 will enter the same, as shown in Fig. 3. As the exhaust nozzle 15 enters the mouth 33, the same is engaged thereby and the exhaust head 32 moved slightly rearwardly on its pivot 37 so as to form a tight joint between the exhaust nozzle 15 and the exhaust head 32. At this time, the front wheels of the truck 8 engage the stop block 7 and properly position said truck in respect to the apparatus for conveying exhaust gases. The conical spider 17 assists in centering the exhaust nozzle 15 in the exhaust head 32 so that a tight joint will be formed therebetween. During the movement of the exhaust nozzle 15 between the abutment plates 31, the lever 20 engages the front edge portion of the carriage 29 and is tripped thereby to open the valve-acting plate 18, as shown by full lines in Fig. 3, and thereby close the exhaust pipe 10 to the muffler 11 and direct the exhaust gases through the port 13, hose 14, nozzle 15 where the same is conveyed by the hose 35 outside of the garage 5. After the valve-acting plates 18 have been opened, the same is held open by the tripping lever 20 which is held by the carriage 29.

When the truck 8 is backed from the garage 5, the exhaust nozzle 15 is withdrawn from the exhaust mouth 33 and from between the abutment plates 31, and at which time the springs 40 return the exhaust head 32 to normal position and the spring 42 returns the carriage 29 to its normal position. During this movement of the truck 8, the tripping lever 20 slides out of engagement with the carriage 29 and together with the valve-acting plate 18 are returned to normal positions under the action of gravity.

During further backing movement of the truck 8 from the garage, the hook 48 en-

gages the bail 50 and collapses the frame, the movement of which is stopped by the fingers 27 coming into contact with the floor of the garage 5. When the frame is stopped by the fingers 27, the hook 48 is tripped out of engagement with the bail 50 and thereby releases the arm 46 to permit the same to swing into its normal position and thereby completes the resetting of the 10 movable parts of the apparatus.

By changing the operative length of the stop chains 52, the carriage 29 may be set at different elevations for vehicles of different makes and the counter-balancing springs 15 28 will hold the collapsible frame wherever stopped by said chains.

What I claim is:

1. The combination with a garage and an exhaust conduit leading therefrom, of a vehicle having an internal combustion engine, and means for automatically connecting the exhaust pipe of said engine to said exhaust conduit.

2. The combination with a garage and an exhaust conduit leading therefrom, of a vehicle having an internal combustion engine, and a cut-out in the exhaust pipe of said engine and having an exhaust nozzle arranged to automatically connect with said exhaust conduit.

3. The structure defined in claim 2 in which the automatic connection between said exhaust pipe and exhaust conduit is effected by a movement of the vehicle in the 35 garage.

4. The structure defined in claim 2 in further combination with means for automatically tripping the cut-out into action at the time the exhaust nozzle is connected to 40 the exhaust conduit.

5. The combination with a garage and an exhaust conduit leading therefrom and having a yieldingly held intake head, of a vehicle having an internal combustion engine, and a cut-out in the exhaust pipe of said engine and having an exhaust nozzle arranged to automatically connect with said intake head by a movement of the vehicle in 45 the garage.

6. The combination with a garage, of a laterally movable yieldingly positioned carriage in the garage, an exhaust conduit leading from the garage and having an intake head carried by said carriage, a vehicle having an internal combustion engine, and a cut-out in the exhaust pipe of said engine and having an exhaust nozzle arranged to automatically move said carriage 55 to position the intake head and to connect

therewith by a movement of the vehicle in 60 the garage.

7. The structure defined in claim 6 in which the intake head is mounted on the carriage for common movement with the exhaust nozzle when connecting therewith. 65

8. The combination with a garage, of a collapsible frame in the garage, an exhaust conduit leading from the garage and having an intake head carried by said frame, a vehicle having an internal combustion engine, a cut-out in the exhaust pipe of said engine and having an exhaust nozzle, and means on the vehicle for setting up said frame by a movement of the vehicle in the 70 garage and positioning the intake head to receive the exhaust nozzle by said movement of the vehicle.

9. The structure defined in claim 8 in further combination with a counter-balancing device for the frame. 75

10. The structure defined in claim 8 in which said means collapses the frame during a reverse movement of the vehicle in the garage.

11. The combination with a garage, of a collapsible frame in the garage, a laterally movable yieldingly positioned carriage on the frame, converging abutments on the carriage, an exhaust conduit leading from the garage and having an intake head mounted 80 on the carriage between said abutments, a vehicle having an internal combustion engine, a cut-out in the exhaust pipe of said engine and having an exhaust nozzle, and a connector on the vehicle for setting up said frame by a movement of the vehicle in the 85 garage and positioning said carriage, whereby by the exhaust nozzle may engage either one of said abutments and move the carriage laterally to position the intake head to receive said exhaust nozzle. 90

12. The structure defined in claim 11 in which said connection automatically releases the frame when set up.

13. The structure defined in claim 11 in 105 which said connection automatically releases the frame when set up, and automatically collapses the same during a reverse movement of the vehicle in the garage.

14. The structure defined in claim 11 in 110 which the cut-out is normally closed, and in further combination with a trip arranged to engage a part on the frame and open said cut-out when the exhaust nozzle is connected to the exhaust conduit.

In testimony whereof I affix my signature.

FRANK S. BALATTA.
